CLAIM

We claim the ornamental design for a powered stacker vehicle, as shown and described.

DESCRIPTION

FIG. 1 is a right upper rear perspective view of a powered stacker vehicle according to our new design;
 FIG. 2 is a left upper rear perspective view thereof;
 FIG. 3 is a right lower rear perspective view thereof;
 FIG. 4 is a right front perspective view thereof;
 FIG. 5 is a left upper front perspective view thereof;
 FIG. 6 is a left lower front perspective view thereof;
 FIG. 7 is a front elevational view thereof;
 FIG. 8 is a rear elevational view thereof;
 FIG. 9 is a right side elevational view thereof;
 FIG. 10 is a left side elevational view thereof;
 FIG. 11 is a top plan view thereof; and,
 FIG. 12 is a bottom plan view thereof.

The broken lines shown in the figures are for the purpose of illustrating portions of the powered stacker vehicle and form no part of the claimed design.
